Filed Jan. 2, 1973, Ser. No. 320,201

Term of patent 14 years

Int. Cl. D21—01

U.S. Cl. D34—5 GP

FIG. 1 is an exploded perspective view of combined game pieces and holder showing my new design;

FIG. 2 is an exploded perspective view of another embodiment thereof;

FIG. 3 is an exploded perspective view of still another embodiment thereof;

FIG. 4 is a perspective view of another embodiment thereof with the pieces resting in the holder; and

FIG. 5 is a perspective view of another embodiment with the pieces resting in the holder.

The opposite sides of the game pieces are plain and colored and the interchangeable pieces shown are lined to indicate contrasting color.

I claim:

The ornamental design for combined game pieces and holder, as shown and described.
